[57] CLAIM

The ornamental design for a support plate for potted plants, substantially as shown and described.

DESCRIPTION

FIG. 1 is a top plan view of a support plate for potted plants showing our new design;

FIG. 2 is a top perspective view thereof;

FIG. 3 is a bottom perspective view thereof;

FIG. 4 is a top perspective view with the absorbent pad removed for ease of illustration;

FIG. 5 is a top plan view of FIG. 4.

FIG. 1

FIG. 2

FIG. 3

FIG. 4

FIG. 5
